US00D551973S

(12) **United States Design Patent** (10) Patent No.: **US D551,973 S**
Hildebrand (45) Date of Patent: **** Oct. 2, 2007**

(54) **SPRAY NOZZLE**(75) Inventor: **George R. Hildebrand**, Independence, MO (US)(73) Assignee: **MeadWestvaco Corporation**, Glen Allen, VA (US)(**) Term: **14 Years**(21) Appl. No.: **29/242,971**(22) Filed: **Nov. 17, 2005**(51) LOC (8) Cl. .... **09-07**(52) U.S. Cl. .... **D9/448**(58) Field of Classification Search **D9/685, D9/448, 447, 435, 434; D23/226, 223, 213; 239/459, 415, 414; D6/542**

See application file for complete search history.

Primary Examiner—Robert M. Spear*Assistant Examiner*—Susan Bennett Hattan(74) *Attorney, Agent, or Firm*—Gordon & Jacobson, PC(57) **CLAIM**

The ornamental design for a spray nozzle, as shown and described.

DESCRIPTION

FIG. 1 is a perspective view of a first embodiment of a spray nozzle in accordance with the present invention;

FIG. 2 is a top view of the spray nozzle of FIG. 1;

FIG. 3 is a left side view of the spray nozzle of FIG. 1, the right side view being a mirror image thereof;

FIG. 4 is a front view of the spray nozzle of FIG. 1;

FIG. 5 is a bottom view of the spray nozzle of FIG. 1;

FIG. 6 is a perspective view of a second embodiment of the spray nozzle in accordance with the present invention;

FIG. 7 is a top view of the spray nozzle of FIG. 6;

FIG. 8 is a left side view of the spray nozzle of FIG. 6, the right side view being a mirror image thereof;

FIG. 9 is a front view of the spray nozzle of FIG. 6;

FIG. 10 is a back view of the spray nozzle of FIG. 6; and,

FIG. 11 is a bottom view of the spray nozzle of FIG. 6.

In all figures, the claimed portions of the design are shaded.
